US0D1112469S

(12) **United States Design Patent** (10) **Patent No.:** **US D1,112,469 S**
(45) **Date of Patent:** **** Feb. 10, 2026**

(54) **MULTIFUNCTION PRINTER**

(71) Applicant: **Zhuhai Pantum Electronics Co., Ltd.**,
Zhuhai (CN)

(72) Inventors: **Aiguo Yin**, Zhuhai (CN); **Zuoxin Yang**,
Zhuhai (CN); **Ke Mou**, Zhuhai (CN);
Xinjing Mao, Zhuhai (CN); **Xinzhaoyi Long**,
Zhuhai (CN); **Jibing Peng**, Zhuhai (CN); **Jiachen Xu**,
Zhuhai (CN)

(73) Assignee: **Zhuhai Pantum Electronics Co., Ltd.**,
Zhuhai (CN)

(**) Term: **15 Years**

(21) Appl. No.: **35/520,149**

(22) Filed: **Dec. 28, 2023**

(80) **Hague Agreement Data**

Int. Filing Date: **Dec. 28, 2023**

Int. Reg. No.: **DM/235315**

Int. Reg. Date: **Dec. 28, 2023**

Int. Reg. Pub. Date: **Mar. 1, 2024**

(30) **Foreign Application Priority Data**

Jun. 29, 2023 (CN) 202330403159.8

(57) **CLAIM**

The ornamental design for a multifunction printer as shown and described.

DESCRIPTION

The file of this patent contains at least one drawing/photograph executed in color. Copies of this patent with color drawing(s)/photograph(s) will be provided by the Office upon request and payment of the necessary fee.

1. Multifunction printer

2. Multifunction printer

1.1 Front view

1.2 Back view

1.3 Left view

1.4 Right view

1.5 Top view

1.6 Perspective view

2.1 Front view

2.2 Back view

2.3 Left view

2.4 Right view

2.5 Top view

2.6 Perspective view

The bottom views of the embodiments 1-2 of the claimed design are omitted since the bottom surfaces are not easily visible or not visible in use and do not contain ornamental features, and form no part of the claimed design.

(Continued)

The portions of the design shown in the orange color are for the purpose of illustrating portions of the multifunction printer and form no part of the claimed design.

1 Claim, 12 Drawing Sheets
(9 of 12 Drawing Sheet(s) Filed in Color)
